UNITED STATES PATENT OFFICE.

LEWIS A. BROWN, OF ST. LOUIS, MISSOURI.

DESIGN FOR A BADGE.

SPECIFICATION forming part of Design No. 25,544, dated May 26, 1896.

Application filed March 30, 1896. Serial No. 585,494. Term of patent 3½ years.

To all whom it may concern:

Be it known that I, LEWIS A. BROWN, of the city of St. Louis, State of Missouri, have invented a new and original Design for a 5 Badge, of which the following is a full, clear, and exact description, reference being had to the accompanying drawings, forming a part hereof.

In the drawings, Figure 1 is a front elevation of a badge embodying my design. Fig. 10 2 is a vertical cross-sectional view taken approximately on the indicated line 2 2 of Fig. 1.

The leading feature of my design consists in a disk or circular body, the circumference 15 of one face of which is slightly smaller than the circumference of the opposite face and upon which smaller face appears a continuous marginal border, and there appearing also upon said smaller face a transversely-positions 20 tioned raised portion.

1 indicates the disk-shaped body, and 2 the raised marginal border. Extending transversely across the front face of the disk or body 1 is the raised portion 3, the face of 25 which is smooth and flat in order to receive suitable marking. Between the raised por-

tion 3 and the raised border 2 are the semicircular depressions 4, the faces of the disk in said depressions being plain and smooth in order to receive suitable marking. The 30 conventional representation of a five-pointed star 5 appears upon the face of the disk within the semicircular depressions 4 immediately above and below the center of the raised portion 3, there being also suitable lines or indicating-marks 6 adjacent the said representation of the star, which lines extend parallel with the raised portion 3. When viewed in front elevation, the badge presents the appearance of a circular body having a pair of 40 oppositely - arranged semicircular depressions, between which is the horizontally-arranged raised body or portion in relief.

I claim—

The design for a badge, as herein shown 45 and described.

In testimony whereof I affix my signature in presence of two witnesses.

LEWIS A. BROWN.

Witnesses:

S. G. WELLS,
MAUD GRIFFIN.
